DESIGN FOR A SEWING ACCESSORY OR SIMILAR ARTICLE

Misao Muramatsu, Los Angeles, Calif.

Application September 12, 1947, Serial No. 141,336

Term of patent 3½ years

(Cl. D3—19)

To all whom it may concern:

Be it known that I, Misao Muramatsu, a citizen of the United States, residing at Los Angeles, in the county of Los Angeles and State of California, have invented a new, original, and ornamental Design for a Sewing Accessory or Similar Article, of which the following is a specification, reference being had to the accompanying drawing, forming part thereof.

Fig. 1 is a front view of a sewing accessory or similar article showing my new design.

Fig. 2 is a rear view thereof.

Fig. 3 is a front view similar to Fig. 1 with the skirt in open position.

Fig. 4 is a perspective view of the sewing accessory or similar article with the doll figure and the skirt removed therefrom.

I claim:

The ornamental design for a sewing accessory or similar article, as shown.

MISAO MURAMATSU.
